BALL ROLLING GAME

Filed Dec. 8, 1927

BY TAKEO USAMI.
Richard D. Brown
ATTORNEY

UNITED STATES PATENT OFFICE.

TAKEO USAMI, OF BROOKLYN, NEW YORK.

BALL-ROLLING GAME.

Application filed December 8, 1927. Serial No. 238,678.

This invention relates to game devices and in particular to one in which a ball is adapted to be projected and a play recorded automatically by the ball projected.

8 A particular object of the invention is to provide in a ball rolling game, an alley, which directs the ball to openings, the selection of which is beyond the control of the individual and to so arrange the scoring devices that the 10 selection of the high scoring members by the individual player cannot be readily accomplished.

15 A further object of the invention is to provide a game of ball rolling in which skill and luck are provided to create interest and one in which the score attained cannot be predicted beforehand, that is, the particular scoring devices cannot be manipulated by a certain throw of the ball as controlled by the 20 player.

25 A still further object of the invention is to provide the simplified construction of ball rolling game which will return the balls to the point of play and which will automatically record a score depending upon the guide runways in which the balls operate.

30 To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

35 Figure 1 is a view in perspective of my improved ball rolling game preparatory to the start of play, the scoring devices or counters being illustrated in their non-recording position and the ball holder being filled with the game balls.

40 Figure 2 is a view in top plan of the ball rolling game, the top thereof being broken away to show the construction of the guide runways which lead the balls after they have dropped through the ball receiving openings in the top piece to suitable troughs in which are pivotally supported the counters or scoring members, and

45 Figure 3 is a view in longitudinal section of my improved game device, the path of one of the balls being illustrated in outline.

50 Referring to the drawings in detail, 5 indicates a housing made of sheet metal or 55 other suitable material and consisting of the

sides 6, top 7 and bottom 8. The forward portion of the housing is constricted as at 9 and at its front end, is open as at 10, the bottom adjacent the front end of the housing being provided with a ball retaining ledge 11, 60 so that the balls when they roll forward after having scored, will be retained in position to be picked out of the housing and replaced in the ball holder.

65 Positioned within the housing 5 is a return flooring 12 which is inclined from rear to front so that the balls are automatically returned to the ball retaining ledge. The top 7 of the housing is provided with a longitudinally extending wall 13 which, for a portion of its length defines a ball rolling alley 14, the wall at its inner end, being shaped in a circle to define a ball receiving field 15 which is provided with openings 16. The 70 openings, of course, are large enough to permit the ball, indicated by the numeral 17 to fall therethrough. The balls are normally retained in a suitable ball holder 18 which is in the nature of an elongated box formed out of the material of the top 7 and disposed 75 at the front edge of the game housing 5.

80 It is of course to be understood that the ball holder 18 may be made separate as may the walls 13 and in fact any of the partitions described or about to be described, can be made up separately and suitably soldered or otherwise fastened into the housing or, in the interest of cheaper manufacture, these various walls may be punched out of the material of the housing, where the same is possible. 85

85 Intermediate the return 12 and upper wall or top of the housing 7, I provide a ball receiving shelf which is disposed at an angle to permit the balls to roll rearwardly, this shelf being indicated by the numeral 19 and 90 being provided with the upstanding walls 20 on the upper surface thereof. These walls 20 define guide runways 21 and the inner extremity of each of the guide runways 21 is located directly beneath one of the ball openings 16. The result is, that when a ball is projected down the alley 14 and dropped through one of the ball openings 16, it drops into one of the guide runways 21 and due to the inclination of the shelf 19, rolls through 95 the guide runway into a suitable compartment 22 of which there is one provided for each of the guide runways 21, a suitable wall 23 being provided to mark off each compartment and to retain the ball in its proper rolling 100 105 110

direction so that it will drop off the end of the shelf 19 on to the ball receiving extension 24 which forms the bottom extremity of the counters 25. These counters, and there is one provided for each of the compartments 22, are pivotally mounted on a shaft 26, the shaft being journalled in the side walls 6 of the housing and in suitable brackets 27 attached thereto. Each of the counters 25 consists of a score tab 28 and a normally up-standing weighted blind 29. This blind is for the purpose of concealing the score on the tab 28 and consequently, the player, when rolling the ball down the alley has no idea of the number that will be scored. The end of the blind or the blind forming extension 29 is weighted so that when the ball drops off the shelf 19 and strikes the extension 24, it will overbalance the counter and the weighted end 29 thereof will maintain the counter in its score showing position.

It is quite evident that there is an opening 16 for each of the alleys 21 and it is also quite evident that if two balls drop into the same opening that only the first ball will score because the weighted end 29 of the counter will maintain the ball receiving extension out of the path of a ball dropping off the shelf 19 thus, a high degree of skill is necessary in order to place each of the balls in a different hole, thus scoring on every counter with every ball.

In order to return the counters to their non-scoring position, I have made use of a finger piece 30 which is pivoted on the end of the shaft 26 and is free to revolve thereabout. This finger piece 30 is provided with a transversely extending wire 31 which rests in suitable cut-outs 32 in the side walls of the housing and in the partitions 23 so that it is out of the way of the end 29 of the counters, thus allowing the same to lie flat on the rod so that the tabs 28 thereof will be in vertical position to effectively display the score thereon. The opposite end of the rod 31 or reset device, as it might better be termed, is pivoted in the bracket 27, hereinbefore mentioned and it is quite evident that pressure on the finger piece 30 will throw the reset device 31 up and any of the extensions 29 that are resting thereon will be returned to their vertical position, the score tab portions 28 being thrown down and the device will then appear as illustrated in Figure 1, after which the balls are taken away from the ball retaining ledge and placed in the ball holder 18 for further play.

It is evident, therefore, that I have provided a ball rolling game device in which the balls may be passed down an alley, will automatically

record a score and will automatically return to the point of play so that it is not necessary for the player to retrieve the ball after every complete play. In making a device of this kind suitable for resort play, a side opening could be provided so that the balls would not return to the player but rather would be in position to be collected by the person operating the game device.

It will be noted that I have also provided counters having blinds thereon so that a player cannot judge in advance what score he can roll by dropping the balls into certain openings.

If desired, the counters may be made of various colors to enhance the appearance thereof.

It is also evident that I have provided a simplified ball rolling game which, due to the uncertainty of its operation, provides amusement and recreation.

It is also evident that I have provided a game device wherein lack of skill in placing the balls in certain openings will result in non-scoring and thus the device will accurately measure the relative skill of competing players.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:—

A game device comprising a ball alley having openings in one end thereof through which the balls drop, a plurality of ball runways under the alley, each of which begins under one of said openings, compartments to which said runways lead, a shaft extending to said compartments, score members in the compartments pivotally mounted on said shaft, said members comprising a weighted portion, a score tab and a ball receiving shelf, the weighted portion being arranged to hide the score tab when the latter is in an indicating position, a reset rod common to all of said score members for returning the same to non-scoring positions after play and a finger piece for operating said reset rod.

In testimony whereof I affix my signature.

TAKEO USAMI. [L.S.]
